MOBILE AIR BLOWING UNIT FOR MAINTAIN- ING BRUSH FIRES AND THE LIKE

William Wallace Allen, Jr., 3604 Mayflower St.,
Jacksonville, Fla.

Filed Mar. 21, 1960, Ser. No. 59,804

Term of patent 14 years

(Cl. D62—2)

Fig. 1

Fig. 5

Fig. 2.

Fig. 3.

Fig. 4.

FIG. 1 is a front elevational view of a mobile air blowing unit for maintaining brush fires and the like, showing my new design.

FIG. 2 is a side elevational view, the opposite side thereof being substantially the same in appearance.

FIG. 3 is a rear elevational view.

FIG. 4 is a top plan view, and

FIG. 5 is a fragmentary perspective view showing a portion of the baffle thereof as seen in the upper right corner of FIG. 1.

I claim:

The ornamental design for a mobile air blowing unit for maintaining brush fires and the like, as shown and described.
